UNITED STATES PATENT OFFICE.

SYDNEY HERBERT VARNDELL, OF CLAPHAM, ENGLAND, ASSIGNOR TO LOCKERBIE AND WILKINSON, BIRMINGHAM LIMITED, OF TIPTON, ENGLAND.

COIN-FREED MECHANISM.

Application filed August 4, 1927, Serial No. 210,612, and in Great Britain February 15, 1927.

This invention relates more especially to a coin-freed mechanism for use with an operated sliding part such as the drawer of a cigarette or sweetmeat delivery machine or 5 the slider of a ticket delivering machine; and has for its object to provide a cheap and compact form of mechanism.

This invention comprises a striking face of an operated sliding part which moves in 10 such a way as to encounter the end of a slider having a slanted face and sliding in a carrier which is yieldingly mounted, and the slider is pressed towards the striking face of the operated sliding part by a relatively 15 weak spring. Rigid with the slider is a rod adapted to move endwise across the coin chute. If therefore an attempt is made to operate the sliding part without inserting a coin, the striking face of the sliding part 20 simply presses forward the slanted face of the slider and engages with an abutment of the carrier whereby further operation is stopped. If, however, a correct coin is inserted, it prevents movement of the rod 25 across the coin chute so that the rod then holds the slider and its slanted face against the pressure of the striking face of the operated sliding part, so that the said striking face rides up the said slanted face and 30 presses down the carrier until it rides over the upper surface thereof.

The invention is described with reference to the drawings herewith, of which:—

Figure 1 is a longitudinal sectional view 35 showing an operated sliding part and coin-free mechanism by which it is locked, the apparatus being shown in the normal locked position.

Figure 2 is a view corresponding to Figure 1, but showing the parts in the position 40 they assume if an attempt is made to operate the slider without inserting a coin.

Figure 3 is a view corresponding to Figure 1; but showing the parts in the position 45 they assume when the sliding part is first operated after the insertion of a coin.

Figure 4 is a section taken on the line 4, 4, 50 of Figure 3 and looking in the direction of the arrow of that figure.

Figure 5 is a view of the apparatus showing the parts in the position they assume 55 when the operated sliding part is drawn out to its fullest extent.

In these drawings:—A is the operated part sliding in a guide C and having a down-

wardly extending striking face *a*. B is a carriage in the form of a lever pivoted at *b* to the guide C and having a coin chute *c* and a sliding rod *d* to which is clamped an L-shaped bracket *e* with a slanting face *f*. 60 The rod *d* with its bracket *e*, is arranged to slide in guides of the carrier B and is constantly pressed in a rearward direction by means of a relatively weak spring *g* against a stop *h* of the carrier. *j j* (see especially 65 Figure 4) are two stops carried upon the lower ends of lugs *k k* which are rigid with the guide C and serve the double purpose of limiting the upward movement of the carrier B by coming against the front of the 70 coin-chute thereof, and of keeping the coin in place while the sliding part A is operated. The carrier B is constantly pressed in an upward direction by means of two coil springs M (one only of which is shown) which connect at their lower ends to lugs *n* of the carrier and at their upper ends to lugs *p* of the guide C. 75

Q is a set screw for clamping the bracket *e* on the rod *d* and allowing for its adjustment thereon. It will be seen that the rod *d* is pointed at its forward end, and that in the normal position of the apparatus it just reaches to the coin chute *c*. 80

If an attempt is made to operate the sliding part A without inserting a coin, the striking face *a* engages the slanting face *f* of the bracket *e* and presses it and the rod *d* back against the force of the spring *g* which is comparatively weak, and the point of 90 the rod simply moves across the coin chute to the position shown in Figure 2, so that the striking face *f* of the sliding part A encounters the rear end of the carrier B whereby it is stopped from further movement. 95

On pushing back the sliding part A and inserting a coin the latter goes down the coin-chute and comes to rest upon the stops *j j*. If now the said part A be operated, 100 the striking face *a* will press upon the slanting face as before but the bracket *e* will not yield forwards because the rod *d* is prevented from moving across the coin chute *c* by the presence of the coin therein. Consequently continued forward movement 105 of the sliding part A presses down the bracket *e* and with it the carrier B, the striking face *a* riding up on to the top of the carrier B all as shown in Figures 3 and 110

5. The pressing down of the carrier B in relation to the guide C causes the coin-chute c to move forward in relation to the stops j and allows the coin to fall from the coin-chute as soon as the striking face a has moved forwards clear of the bracket e, and has ceased to exert forward pressure thereon. The bracket e and rod d then assume their normal position in relation to the carrier B. When the sliding part A is moved back to its normal position the parts go back to the position shown in Figure 1.

It will now be seen that a very delicate setting of the rod d in relation to the bracket e will have the effect of discriminating between different thicknesses of coins inserted, because the rod may be so set in relation to the bracket that a coin which exceeds a certain thickness will be stopped by the point of the rod, while a coin which is too thin, by allowing a certain amount of forward movement of the rod in relation to the coin-chute may cause the striking face a to encounter the rear end of the carrier C and prevent further forward movement of the sliding part A. The stops j j can be so arranged that they will allow a coin of too small a diameter to pass clear through, and the width of the coin chute may be such as to render it impossible to insert a coin which exceeds a predetermined diameter.

The reason why the rod d is pointed is that, if a washer is inserted in the coin-chute in lieu of a coin, the point of the rod will pass through the washer and the parts will remain locked. Also the point will pierce cardboard or soft metal and the parts will remain locked if an attempt is made to free the mechanism with discs of either of these materials.

It will now be clear that the apparatus can be adjusted for the use of two or more cams of equal size at the same time simply by correctly setting the bracket e on the rod d.

Having fully described my invention, what I claim and desire to secure by Letters Patent is:—

50 1. In coin-free apparatus, a relatively moving part, a striking face of such part, a yielding slide with a slanting rear end against which said striking face engages, a guide for the relatively moving part, a carrier yieldingly mounted in relation to the said guide and carrying said slide, a stop rigidly mounted in relation to the guide for limiting the upward movement of the carrier, a coin-chute into which the forward end of the said slide is adapted to pass, means by which the coin is stopped in the coin chute opposite the slide whereby the latter is prevented from forward movement under the action of the said striking face so that said striking face rides up the said

slanting end of the slide depressing the carrier and riding thereover, and means by which the coin is subsequently released.

2. In coin-free apparatus, a relatively moving part, a striking face of such part, a yielding slide with a slanting end against which said striking face engages, a guide for the relatively moving part, a carrier yieldingly mounted in relation to the said guide and carrying said slide, a stop rigidly mounted in relation to the guide for limiting the upward movement of the carrier, a coin-chute into which the forward end of the said slide is adapted to pass, a pair of stops projecting into said coin-chute to stop the coin in position opposite the slide whereby the latter is prevented from forward movement under the action of the said striking face so that the latter rides up the said slanting end of the slide depressing the carrier and riding thereover and means by which the coin is subsequently released.

3. In coin-free apparatus, a relatively moving part, a striking face of such part, a yielding slide having a slanting rear end against which said striking face engages, a guide for the relatively moving part, a carrier pivotally mounted in relation to the said guide and carrying said slide, a coin-chute in the carrier into which chute the forward end of the said slide is adapted to pass, a pair of stops projecting into the coin-chute whereby the coin is stopped opposite the slide and said stops passing out from under the coin to release it when the carrier has moved a predetermined distance.

4. In coin-free apparatus, a relatively moving part, a striking face of such part, a sliding spring-pressed rod with a pointed forward end, a bracket adjustably mounted on said rod and having a slanted rear end against which said striking face engages, a guide for the relatively moving part, a carrier yieldingly mounted in relation to the said guide and carrying said slide, a stop rigidly mounted in relation to the guide for limiting the upward movement of the carrier, a coin-chute into which the forward end of the said slide is adapted to pass, means by which the coin is stopped in the coin chute opposite the slide whereby the latter is prevented from forward movement under the action of the said striking face so that the latter rides up the said slanting end of the slide depressing the carrier and riding thereover, and means by which the coin is subsequently released.

5. In coin-free apparatus, a relatively moving part, a striking face of such part, a yielding slide with a slanting rear end against which said striking face engages, a guide for the relatively moving part, a carrier pivotally mounted in relation to the said guide and carrying said slide, means by which said carrier is constantly pressed

in an upward direction, a stop rigidly mounted in relation to the guide for limiting the upward movement of the carrier, a coin-chute in the carrier into which chute the forward end of the said slide is adapted to pass, means by which the coin is stopped in the coin chute opposite the slide whereby the latter is prevented from forward movement under the action of the said striking face so that the latter rides up the said slanting end 10 of the slide depressing the carrier and riding thereover, and means by which the coin is subsequently released.

In witness whereof I have hereunto signed my name this 19th day of July, 1927.

SYDNEY HERBERT VARNDELL.
